UNITED STATES PATENT OFFICE.

CARL T. SCHAEFER, OF HONOLULU, TERRITORY OF HAWAII.

SWITCH-OPERATING DEVICE.

1,116,330.

Specification of Letters Patent.

Patented Nov. 3, 1914.

Application filed September 24, 1913. Serial No. 791,602.

To all whom it may concern:

Be it known that I, CARL T. SCHAEFER, a citizen of the United States, residing at Honolulu, Territory of Hawaii, have invented new and useful Improvements in Switch-Operating Devices, of which the following is a specification.

This invention relates to a switch operating device adapted for use on street railings 10 cars to be operated by the motorman for the purpose of opening and closing a track switch, the object of the invention being to provide a simple, reliable, efficient and easily-manipulated type of switch operating or throwing device which may be readily installed upon conventional styles of cars and which is applicable for use in throwing either right or left hand switches.

The invention consists of the novel features of construction, combination and arrangement of parts hereinafter fully described and claimed, reference being had to the accompanying drawing in which:

Figure 1 is a sectional view of the portion 25 of the end of a street car showing the application of the invention. Fig. 2 is a sectional plan view of the device. Fig. 3 is a front elevation through the device, showing the box or casing and floor or platform 30 of the car in section. Fig. 4 is a detail view showing modified form of treadle or foot piece.

Referring to the drawing 1 designates the floor or platform of a street car, below which is arranged a box or casing 2. This box or casing is provided with bearings 3 for a vertical rod or shaft 4, and is fitted at its upper end in an opening 5 in the floor and suitably fastened to a supporting plate 6 secured to the floor, through which plate the rod or shaft 4 also extends. The said rod or shaft 4 is also journaled at its upper end in a bearing bracket 6a fastened to the dash board of the car, whereby it is firmly 45 supported in position.

The rod or shaft 4 carries at its lower end a wedge-shaped switch throwing projection, shoe or tip 7, which normally lies slightly above the plane of the track, and 50 is adapted to be depressed to enter between a fixed track rail and the tongue of the switch so that the latter may be thrown. The said projection, shoe or tip 7 is slidably offset from the plane of the shaft so 55 that it is applicable to the car for use in throwing switches to the right or left.

The rod or shaft 4 is mounted to slide vertically and oscillate about the axis of the shaft in the bearings 3 and plate 6, and is normally sustained by a coiled spring 8 arranged within the box or casing 2. As shown, the spring surrounds the rod or shaft between the bottom of the casing and an abutment disk 9 secured to the rod or shaft, and exerts its expansive energy on said abutment head or disk to hold the shaft in an elevated position, while permitting of its being depressed to adjust the shoe 7 for action. The head or disk 9 is adapted to abut against the plate 6 to limit the upward movement of the rod or shaft and normally maintain the parts in a prescribed elevated position. The upper end of the rod or shaft carries a crank handle 10, whereby it may be oscillated, and below said crank handle a treadle or foot piece 11 is fixed to the rod or shaft in such relation to the plate 6 that it will abut against said plate and limit the downward movement of the shaft when the shoe 7 is depressed to working position. This treadle or foot piece 11 may be in the form of a disk as shown in Figs. 1, 2 and 3, arranged to surround the rod or shaft so that it may be engaged by either foot or it may be in the form of a treadle or foot piece 12 having right and left hand foot portions, as shown in Fig. 4.

In practice the device is normally supported above the level of the track, so that the shoe 7 will travel clear of all obstructions. When the motorman desires to throw a switch, he brings his car to a stop at a point immediately in rear of the switch tongue and then depresses the shaft to lower the shoe 7 to working position so that it will enter the space between the tongue and the track rail. While the shaft is still held depressed the motorman by turning the crank handle 10 may oscillate, the shoe 7 in the proper direction to throw the switch tongue. Upon releasing the treadle the spring 8 will thereupon return the device to normal position.

It will of course be understood that by means of the device a switch tongue may be thrown in either direction to set it for the proper travel of the car in either direction at the points of intersection of tracks. The spring may be fastened as shown, to the box or casing and the shaft or abutment in such manner that it will be tensioned when the shaft is oscillated about its axis, to auto-

matically swing the shaft and shoe back to normal position after actuation.

Having thus described my invention, I claim:

- 5 The combination with a car, of a box or casing arranged below the floor of the car and fitted at its upper end in an opening therein, said casing having a bearing opening at its lower end, a bearing plate secured
10 to the floor of the car and supporting said box or casing, and also closing the top thereof, an intermediate bearing member within the box or casing between said bearing opening and bearing plate, a rod or
15 shaft extending vertically through said bearing opening, bearing plate and intermediate bearing member, said rod or shaft extending below the casing and above the car floor and being slidably and axially
20 movable, a tongue-throwing shoe upon the

lower end of said rod or shaft, an abutment upon the shaft within the box or casing adapted to bear against the plate to limit the upward movement of the shaft, a coiled spring inclosed in the casing about the 25 shaft between the intermediate bearing and abutment and acting on the latter to hold the shaft normally elevated, a foot piece whereby the shaft may be depressed and adapted to abut against the plate to 30 limit the downward movement of said shaft, and a handle whereby the shaft may be oscillated about its axis to adjust the shoe laterally.

In testimony whereof I affix my signature in presence of two witnesses.

CARL T. SCHAEFER.
